UNITED STATES PATENT OFFICE.

JAMES W. CALTA, OF PLATTE, SOUTH DAKOTA.

SICKLE-GUARD-POINT SHIELD.

1,083,662.

Specification of Letters Patent.

Patented Jan. 6, 1914.

Application filed December 5, 1912. Serial No. 735,063.

To all whom it may concern:

Be it known that I, JAMES W. CALTA, a citizen of the United States, residing at Platte, in the county of Charles Mix and 5 State of South Dakota, have invented certain new and useful Improvements in Sickle-Guard-Point Shields; and I do hereby declare the following to be a full, clear, and exact description of the invention, such as 10 will enable others skilled in the art to which it appertains to make and use the same.

This invention relates to harvesting machines, and it more particularly relates to an attachment for sickle-guard-points.

15 An object of the invention is to provide an easily applicable attachment, whereby the points of sickle-guards may be shielded, for preventing their engagement with corn stalks, stumps, etc.

20 Another object of the invention is to provide a device of this character which may be applied to sickle-guards of different sizes and tapers.

Another object of the invention is to provide 25 a sickle-point shield which is formed from ordinary mercantile stock of steel tubing, so as to insure the minimum cost of manufacture.

A still further object of the invention is 30 to provide a device of this character formed from somewhat resilient material, so that the tongues thereof will constitute clamping elements, whereby the shields will be securely held in position on the guards.

35 With these objects in view, the invention consists in the improved construction, arrangement and combination of parts of a device of the character specified, which will be hereinafter fully described, and afterward 40 specifically claimed.

In the accompanying drawings, which illustrate an approved embodiment of my invention, Figure 1 is a perspective view of an ordinary sickle-guard having my improved 45 guard-point shield in position thereon. Fig. 2 is a horizontal sectional view through the shield seated on a fragmental end portion of a sickle-guard. Fig. 3 is a side elevation view of one of the guard-point shields before being driven in place on the sickle-guard-point, and, Fig. 4 is a vertical sectional view through a slightly modified form of my guard-point shield, in position on a guard-point.

55 Referring to these drawings, in which similar reference characters designate cor-

responding parts throughout the several views, a sickle-guard of ordinary construction is designated by the numeral 5, and on the point or front end portion 6 of the 30 guard is seated the shield 7. This shield is formed from metal tubing, preferably steel, of a medium grade, so that it is not only tough, but also possessed of some resiliency or elasticity. In the process of manufacture, 35 the tubing is first cut into suitable lengths and each length is then flattened at one end and trimmed so as to present an arcuate front edge 8. The cylindrical portion 9 is then slotted at 10, so as to form any number 40 of tongues 11. In the present instance, four tongues are employed, two of which are illustrated in Fig. 2, the other two being removed with the omitted section; however, it is obvious that any number of tongues 45 11 may be formed, if desired.

It will be seen that when the point or front end portion 6 is forced into the shield, between the tongues 11, or the shield is driven onto the point 6, the tongues will be 50 spread apart at their free ends, so as to conform to the taper of the sickle-guard-point, while because of the resiliency of said tongues, they will bind or clamp the guard tightly, and securely hold the shield on the 55 guard. When used on new guard-points, the rough surface of said guard-point and that of the internal surface of the tongues will be sufficient to hold the shields in place by friction; but when the guards have been 60 used for a while, and have therefore become polished at their points, it may become necessary to provide additional means for securing the shields in place and may sometimes be necessary to roughen or abrade the 65 exterior surface of the point, or the interior surfaces of the resilient tongue.

While I do not limit myself to any specific means for holding the shields in place, I herewith illustrate, in Fig. 4, another means 70 100 whereby the shield may be tightly held upon the point, in which illustration a shield 7' having a lug 7^a formed thereon, and while I have shown this lug as being struck up or formed at the free end of one of the tongues, 75 it should be understood that the invention is not dependent upon a lug so formed at the end of the tongue, as obviously, it could be formed on any other portion of any of the tongues. In applying this modified 80 105 form, the contiguous surface of a guard-point has been previously notched at 6', and

a file or other proper tool may be used for forming these notches, but in practice, the notches could more quickly and easily be made with a cold-chisel and hammer. It is 5 obvious, that when a guard-point has been thus fitted with one of my improved shields, the latter is permanently secured in place; and when all of the guards have been so shielded, the guards can no longer puncture 10 and thus carry corn stubbles and stumps through the grain which is being harvested, so as to deflect the grain straws out of the path of the sickle and prevent the harvesting of said grain straws.

15 It will be seen that I have provided a device of this character which is fully capable of attaining the foregoing objects, and in a thoroughly practical and efficient manner.

I do not limit my invention to the exact 23 details of construction, combination and arrangement of parts, as herewith illustrated and described, but my invention may only be limited by a reasonable interpretation of the claims.

I claim:—

1. A sickle-guard-point-shield comprising a hollow body having a forwardly extended flat end portion, said hollow body being flared rearwardly from the flat portion and longitudinally slitted, forming resilient 30 tongues whereby, when the guard is driven upon the point, said tongues will clamp and frictionally engage the point and hold the guard thereon.

2. A sickle-guard-point-shield comprising 35 a hollow flared body longitudinally slitted forming resilient tongues which when the guard is driven upon the point will clamp and frictionally engage said point, said guard having also a forward flat extension 40 having an arcuate forward edge.

In testimony whereof I have signed my name to this specification in the presence of two subscribing witnesses.

JAMES W. CALTA.
